No. 696,615.

Patented Apr. 1, 1902.

S. WILSON.

VALVE.

(Application filed May 21, 1901.)

(No Model.)

UNITED STATES PATENT OFFICE.

SYLVESTER WILSON, OF CLOQUET, MINNESOTA.

VALVE.

SPECIFICATION forming part of Letters Patent No. 696,615, dated April 1, 1902.

Application filed May 21, 1901. Serial No. 61,283. (No model.)

To all whom it may concern:

Be it known that I, SYLVESTER WILSON, a citizen of the United States, residing at and whose post-office address is Cloquet, in the 5 county of Carlton and State of Minnesota, have invented new and useful Improvements in Valves, of which the following is a specification.

This invention relates to safety-valves for 10 sawmill-carriages; and the principal object of the invention is to provide a valve of such construction as to render the valve automatic for the purpose of instantly shutting off the supply of steam in case breakage occurs in 15 the valve-operating connections, the valve being constructed and arranged to close by gravity.

Sawmill-carriages are usually driven by the piston-rod of a steam-cylinder, and as there 20 are oftentimes several men working on the carriage, which travels very rapidly, should the valve connections break or get out of order the sawmill-carriage is liable to run away, with the result that the men employed on the 25 carriage are often seriously injured.

It is therefore the object of this invention to provide a valve which will close automatically and stop the carriage in case the valve connections break or get out of order.

30 With the above object in view the invention consists in the novel construction, combination, and arrangement hereinafter fully described, illustrated, and claimed.

The accompanying drawing represents a 35 diagrammatical elevation of the steam-cylinder of a sawmill-carriage and the improved valve mechanism applied thereto.

Referring to the drawing, 1 designates the steam-cylinder, in which is arranged a reciprocating piston mounted upon the piston-rod 40 2, passing through a suitable stuffing-box 3, and adapted to connect with the sawmill-carriage for reciprocating the latter.

The steam-supply pipe (represented at 4) is 45 connected at its opposite ends to twin valve-casings 5, which in turn are placed in communication with the opposite ends of the steam-cylinder 1 by means of the terminal conduits 6. Each valve-casing comprises an 50 induction-port 7, with which the steam-supply pipe 4 communicates, and an eduction-

port 8, with which one of the terminal conduits 6 communicates. Each valve-casing also comprises a valve-chamber 9, which extends vertically and in which is arranged a 55 reciprocating valve 10, provided with a pair of terminal heads 11 and 12, adapted to alternately open and close the induction and eduction ports, as well as the exhaust-port 13, which is in communication with the exhaust- 60 pipe 14. Each valve is further provided with a valve-stem 14^a, passing through a stuffing-box 15 in the bottom of the valve-casing. One of the stems 14^a is pivotally connected to the middle arm 16 of a T-lever 17, to another 65 arm of which is attached the valve-operating connection 18. The remaining arm of the T-lever has attached thereto a connecting-rod 19, which at its opposite end connects with an elbow-lever 20, associated pivotally with 70 the lower extremity of the other valve-stem 14^a. By means of the construction just described the valves are simultaneously reciprocated in opposite directions for alternately supplying steam to the opposite ends of the 75 cylinder 1 and exhausting the steam therefrom.

It will be seen from the foregoing description that by reason of the fact that the valves are arranged to reciprocate in vertical paths 80 should the connecting-rod 19 or the operating-levers or their pivots become broken or disarranged the valves, which are of considerable weight, will gravitate to the bottoms of the valve-chambers, with the result that the 85 supply of steam to the cylinder will be instantly cut off and the movement of the sawmill-carriage checked. The sawmill-carriage is thus prevented from running away and injuring the workmen thereon. 90

Having thus fully described my invention, what I claim as new, and desire to secure by Letters Patent, is—

The combination with the steam-cylinder of a sawmill-carriage; of twin valves comprising valve-casings respectively in communication with the opposite ends of the cylinder and each having an exhaust, a steam-supply pipe leading to both valve-casings, vertically-movable valves adapted to alternately open and close the steam ports and exhausts, and reversely-disposed elbow-le- 95 100

vers coupled together and connected with said valves to simultaneously admit steam to one end of the cylinder and exhaust from the opposite end, both valves being adapted to automatically and simultaneously shut off the supply of steam to the cylinder in case of breakage of the valve-operating connections.

In testimony whereof I affix my signature in presence of two witnesses.

SYLVESTER WILSON.
